United States Patent Office.

WILLIAM HARTLEY MILLER, OF PHILADELPHIA, PENNSYLVANIA.

Letters Patent No. 77,204, dated April 28, 1868.

IMPROVED PACKING FOR ENGINES, PUMPS, &c.

The Schedule referred to in these Letters Patent and making part of the same.

TO ALL WHOM IT MAY CONCERN:

Be it known that I, WILLIAM HARTLEY MILLER, of the city of Philadelphia, in the county of Philadelphia, and State of Pennsylvania, have invented a new and useful improvement whereby the Packing of Stuffing-Boxes of Engines, Pumps, &c., and of other joints of machinery, may be greatly improved; and I hereby declare that the following is a full, clear, and exact description thereof.

The nature of my invention consists in the use of calcimine, china-clay, white clay, or their equivalents, in combination with other materials for packing.

Calcimine is a well-known article of white, used for whitening walls, and for other purposes, rendered practically free from grit, has a soft-soapy feel, and it can be pulverized and used in a dry state, or it can be compounded with liquids or melted wax and used as a paste. China-clay and white clay are similar in their nature to calcimine.

When calcimine is used in combination with fibrous material, it protects the fibre from the effects of the heat, and becomes a good substitute for soapstone as an ingredient of packing. It can be applied to any form of packing by combining it with lubricants, metallic, fibrous, or other materials used in the manufacture of packing. In some instances, I combine it with fibrous material by taking a given number of strands or threads of fibrous material, and twisting, braiding, plaiting, or weaving them into rope-form, securing thereby the calcimino in a joint or stuffing-box.

I do not limit myself to any specific form or method of application.

What I claim as my invention, and desire to secure by Letters Patent, is—

1. The use of calcimine, china-clay, or white clay, or their equivalents, as a substitute for dry-powdered soapstone, and other dry-powdered substances, in their combination with fibrous or other materials in the manufacture of packing.

2. The use of calcimine, china-clay, white clay, or their equivalents, for the purpose above described, in the manner above described, or any other practical application thereof, whereby said substances become ingredients of packing for the stuffing-boxes of engines, pumps, and for the joints of other machinery.

Witnesses:

E. W. MILLER,
E. CONOLEY.
